UNITED STATES PATENT OFFICE.

NICKLAS FRANZEN, OF WALTON, PENNSYLVANIA.

DESIGN FOR A PLATE OF GLASS.

No. 38,251.

Specification for Design.

Patented Sept. 25, 1906.

Application filed August 13, 1906. Serial No. 330,485. Term of patent 14 years.

To all whom it may concern:

Be it known that I, NICKLAS FRANZEN, a citizen of the United States, residing at Walton, in the county of Allegheny and State of Pennsylvania, have invented a new, original, and ornamental Design for Plates of Glass, of which the following is a specification, reference being had to the accompanying drawing, forming part thereof.

The figure is a plan view of a sheet of plate-glass, showing my new design.

I claim—

The ornamental design for a plate of glass, as shown.

NICKLAS FRANZEN.
